Primary Examiner—James J. Gill*Assistant Examiner*—Marvin Smolar*Attorney*—A. T. Stratton, W. D. Palmer and D. S. Buleza[57] **ABSTRACT**

A rigid open-ended sleeve of plastic or other light-transmitting material is suspended in telescoped spaced-apart relationship with the glass envelope of an electric lamp by slipping the sleeve over a pair of spaced rubber grommets that compressively grip the envelope. The grommets effect a force fit with the sleeve and the latter is retained in place on the lamp solely by the grommets. In the case of a fluorescent lamp or other type of low-pressure electric discharge lamp, the sleeve serves both as a protective shield against accidental breakage of the envelope and as an insulating jacket which permits the lamp to operate efficiently at low ambient temperatures (-18°C for example). The sleeve can be fabricated from colored plastic or glass to provide a low-cost fluorescent lighting unit that emits light of a selected color and is thus especially adapted for use in outdoor decorative lighting applications.

**TUBULAR ELECTRIC DISCHARGE LAMP WITH
INTEGRAL PROTECTIVE-INSULATING SLEEVE**

CROSS REFERENCE TO RELATED APPLICATION

An electric discharge lamp having a tubular glass envelope that is protectively enclosed in a tight-fitting sleeve of shrunk oriented plastic, or in a rigid loose-fitting sleeve that is held in place by shrunk plastic sleeves, is disclosed in application Ser. No. 586,115 of George S. Evans, filed Oct. 12, 1966.

BACKGROUND OF THE INVENTION

1. Field of the Invention

This invention relates to electric lamps and has particular reference to an improved fluorescent lamp assembly that is adapted for use in lighting applications where protection against accidental lamp breakage is desired and/or low ambient temperatures prevail.

2. Description of the Prior Art

Fluorescent lighting units having integral protective and thermal-insulating shields or jackets are well known in the art. Heretofore, the jacket was held in spaced-apart enclosing relationship with the lamp envelope by a pair of resilient caps or gaskets that were slipped over the based end portions of the lamp and engaged the adjacent ends of the sleeve — thereby providing a sealed air space around the entire lamp envelope. A fluorescent lighting unit constructed in this manner is disclosed in U.S. Pat. No. 3,124,307 issued Mar. 10, 1964 to T. E. Hoskins et al. In a more recent design, a portion of the inner surface of a protective glass jacket is coated with reflective material and the ends of the jacket are inserted into annular recesses in sealing rings of resilient material that are force-fitted over the ends of the lamp. A jacketed fluorescent lamp assembly of such construction is disclosed in U.S. Pat. No. 3,179,792 issued Apr. 20, 1965 to H. Weiss.

While such jacket assemblies achieved the desired objectives of protecting the lamp envelopes against accidental breakage and thermally insulating the lamps, they were difficult to manufacture on a mass-production basis and were quite expensive since they required precision-molded sealing caps or gaskets. Moreover, it has been found that when a plastic jacket was used the jacket expands and contracts to a greater degree than the glass envelope with temperature changes, thus causing the sleeve and gaskets to gradually separate. Under certain low-temperature conditions, it has also been found that ice sometimes forms under the rubber gaskets which eventually forces them off of the ends of the lamp.

SUMMARY OF THE INVENTION

The aforementioned problems and disadvantages encountered with the prior art designs and structures are averted in accordance with the present invention by mounting a tubular open-ended sleeve on the lamp with a pair of narrow grommets of resilient material that compressively grip the lamp envelope and are located inwardly from the ends of the sleeve and the base members that are attached to the ends of the lamp envelope. The wall thickness of the grommets is so correlated with the inside diameter of the sleeve that the latter makes a tight frictional fit with the grommets and is securely held in place on the lamp. The open ends of

the sleeve are not restricted or constrained in any manner and the sleeve is thus, suspended in telescoped and shielding relationship with the lamp envelope. The sleeve is accordingly free to expand and contract relative to the envelope without slipping off of the lamp and can thus be made of plastic, even though the lamp is intended for use in low-temperature environments. The resulting lamp assembly is light in weight, easy to assemble and requires inexpensive sleeve and sleeve-retaining components.

BRIEF DESCRIPTION OF THE DRAWING

A better understanding of the invention will be obtained by referring to the exemplary embodiment shown in the accompanying drawing, wherein:

FIG. 1 is a side elevational view, partly in section, of a fluorescent lighting unit incorporating the invention; and

FIG. 2 is an end view of the lighting unit.

**DESCRIPTION OF THE PREFERRED
EMBODIMENT**

The improved lighting unit 10, as illustrated in FIGS. 1 and 2, consists of an elongated fluorescent lamp L that has a cylindrical glass envelope 12 which is protectively disposed within an open-ended tubular sleeve 14 of rigid light-transmitting material. The sleeve 14 is suspended in spaced-apart telescoped relationship with the envelope 12 by a pair of resilient band-like members such as narrow rubber grommets 15 and 16 that are compressively sandwiched between the sleeve and the ends of the lamp envelope, as shown. As will be noted, the sleeve 14 is shorter than the overall length of the lamp L but is of substantially the same length as the lamp envelope 12 and is also cylindrical but slightly larger in diameter so that an annular air space S is provided which surrounds and extends along almost the entire length of the envelope. The sleeve 14 can be fabricated from any suitable light-transmitting material, such as glass, but is preferably made of plastic in order to reduce the weight and cost of the lighting unit 10.

In the case of a conventional 40 watt T12 fluorescent lamp L that has an outer diameter of about 38 mm. and a nominal overall length of approximately 122 centimeters, the rubber grommets 15 and 16 have an inside diameter of about 38 mm. and are spaced a predetermined distance X inwardly from the respective open ends of the sleeve 14 and from the base members 17 that are attached to the sealed ends of the envelope 12. For a lamp of the size described, this spacing is approximately 6 mm. and allows the sleeve 14 to move relative to the lamp L (as the ambient temperature changes) without becoming disengaged from the envelope 12.

The fluorescent lamp L is of conventional construction and contains an ionizable medium consisting of a suitable starting gas, such as neon or a mixture of neon and argon at low pressure, and a predetermined amount of mercury. A pair of spaced electrodes (not shown) are sealed into the envelope 12 and are electrically connected to pin terminals 18 anchored in each of the respective base members 17. The energized electrodes, in conjunction with the mercury and gas fill, initiate and sustain an electric discharge within the lamp L which excites a layer of phosphor (not shown) coated

on the inner surfaces of the envelope 12 in the well known manner.

In the case of an envelope which has an outer diameter of about 38 mm. as mentioned above, excellent results have been obtained by using a clear transparent 5 sleeve of extruded polycarbonate resin having a wall thickness of approximately 1 mm. and an inside diameter of about 39.6 mm. The rubber grommets were 3 mm. wide and had a uniform wall thickness of 1/16 inch (about 1.6 mm.). The air space between the sleeve 10 and envelope was, accordingly, 1.6 mm. and this permitted the lamp to operate at ambient temperatures in the order of -18°C with practically no loss in light output.

Polycarbonate resin sleeves are available in a variety 15 of tubular sizes, wall thicknesses and colors (red, pink, gold, blue, green, etc.).

With lamps longer than 122 centimeters (for example, 183 cm. or 244 cm.), three grommets are 20 preferably used and are spaced apart distances equal to about one-third of the lamp length. If a plastic sleeve is used, the inward-spacing dimension X will also be increased to accommodate the larger increments of longitudinal expansion and contraction which will occur under varying ambient temperatures due to the longer 25 length of the sleeve.

It will be apparent from the foregoing that the invention provides an inexpensive lighting unit that is light in weight and can be easily and efficiently assembled by simply placing the grommets on the finished lamp and 30 forcibly slipping the sleeve over the grommets. In the case of fluorescent lamps or other electric discharge lamps, the invention permits the units to be safely used in applications where accidental bulb breakage would be hazardous and also provides efficient colored light 35 sources that can be used in outdoor decorative lighting applications, such as amusement parks and the like.

We claim as our invention:

1. A lighting unit comprising, in combination; 40
an electric lamp having a tubular glass envelope, a protective shield for said envelope consisting of a rigid tubular open-ended sleeve of light-transmitting plastic that (a) is larger than and is suspended in spaced-apart telescoped relationship with said envelope, (b) is shorter than said lamp, 45 and (c) expands and contracts to a greater degree than said glass envelope under varying ambient temperature conditions, and means retaining said plastic sleeve on the lamp in the

aforesaid relationship with said envelope comprising a plurality of narrow band-like members of resilient material that encircle the envelope at spaced points along its length and are located between said envelope and sleeve, said retaining members being of such size that they compressively grip the encircled parts of the envelope and are in tight frictional engagement with the overlying encircling portions of said sleeve so that the sleeve is securely anchored in place on the lamp solely by said retaining members,

the retaining members that are located at the ends of said lamp being disposed inwardly a predetermined distance from the respective ends of both the sleeve and envelope such that the plastic sleeve is free and able to expand and contract relative to the glass envelope under varying ambient temperature conditions without forcing the outermost retaining members off of said lamp.

2. The combination of claim 1 wherein; said electric lamp comprises a fluorescent lamp that contains an ionizable medium and a pair of spaced electrodes which are connected to terminals that are located at and protrude beyond the respective ends of the lamp envelope and are anchored in base members fastened to the ends of said envelope,

said open-ended plastic sleeve is of substantially the same length as the envelope and is so positioned that said base members and terminals are exposed, said retaining members comprise rubber grommets that are spaced inwardly from the respective base members, and

the distance the outermost grommets are spaced inwardly from the respective ends of the sleeve and base members is correlated with the length of the lamp and increases as the lamp length increases.

3. The combination of claim 2 wherein; said open-ended sleeve is composed of polycarbonate resin, and
said rubber grommets are of substantially uniform wall thickness.

4. The combination of claim 2 wherein; said fluorescent lamp has a nominal length of approximately 122 centimeters, and
the grommets located at the ends of said lamp are disposed approximately 6 mm. inwardly from the respective ends of the sleeve and base members.
